WILHELM STUBER, OF CANNSTATT, GERMANY, ASSIGNOR TO MAUSER-WERKE A.-G.,
OF OBERNDORF-ON-THE-NECKAR, GERMANY

CALCULATING MACHINE

Application filed July 28, 1928, Serial No. 396,050, and in Germany July 28, 1927.

My invention relates to calculating machines, and more particularly to machines of the type in which ten keys are provided and which have a printing mechanism, although I do not wish to be limited to a combined calculating and printing machine and no printing mechanism will be described in the following specification.

It is an object of my invention to improve a machine of this type, particularly with respect to its tens transfer, to wit, the mechanism which upon addition or subtraction causes, when a given totalizer wheel has been operated, the wheel at the left or at the right of that wheel to be rotated when "zero" is over or understepped.

To this end I provide positive and absolutely reliable means for effecting the tens transfer which are so designed as to result in a very compact mechanism, provide excellent facilities for supporting the fingers by which the tens transfer is operated, and are particularly favourable with respect to quantity production.

In the drawings affixed to this specification and forming part thereof a totalizer embodying my invention is illustrated diagrammatically by way of example at the scale of about 2½ times its real size.

In the drawings,

Fig. 1 is a longitudinal vertical section of the totalizer,

Fig. 2 is a section on the line II—II in Fig. 1,

Fig. 3 is an end elevation viewed from the right in Fig. 1,

Fig. 4 is a plan view showing a detail of the mechanism,

Fig. 5 is an elevation of a tens-transfer lever,

Fig. 6 is an end elevation of the lever viewed from the left in Fig. 5, and

Fig. 7 is another detail of the mechanism.

Referring to the drawings, the totalizer comprises two frame plates 32 and 33 which

may be fulcrumed on the machine by pins 41, and are connected by stays 8, 10', 17, 37 and 46, brackets 34, 34 and a stay 21 between such brackets, it being understood that the pin 41 and the bracket 34 which are shown at the plate 32 in Fig. 1, are duplicated at the opposite plate 33. 22b is a shaft extending through the frame from end to end and projecting at the left of the frame beyond its plate 33, where a handle, a gear wheel, a pulley or any other part, not shown, for imparting rotation to the shaft 22b, is keyed or otherwise secured on the shaft 22b so as to rotate in unison therewith. Keyed on the shaft 22b are disks 22a which are recessed at one end, as best seen in Figs. 2 and 4, and flat plates 23', each with a pair of teeth 23 which are inserted between the recessed disks 22a. In this manner the disks 22a and the disks 23' make up a cylinder 22 which rotates with the shaft 22b. 22c is a pin extending through all disks and plates 22a and 23' on the cylinder 22 by which they are held in a predetermined relative position. Each disk 22a is provided with a pair of fingers 24 and 25, the finger 24 being shown in Figs. 2 and 4. The fingers are mounted to rock about pins 29, 29 in the disks 22a. 36 are pins arranged in pairs at opposite sides of the fingers 24 and 25 and projecting in to the recessed portions of the disks, as best seen in Fig. 4.

1, 1 are dial wheels which are free to rotate on the stay 46, each wheel bearing on its perimeter the digits 0 to 9, and an abutment 2 in the vicinity of the digit "0". The abutments 2 are inserted in slots 44 of the respective dial wheels 1, and held therein by screws 45. 3 is a U-shaped frame or bar which is fitted to rock about the stay 8 and provided with a handle 3'. This frame or bar cooperates with the abutments 2, for instance, when printing sums, the printing mechanism being set for the sum which has been calculated while the dial wheels are

set to "0". The number of dial wheels 1 is equal to the maximum number of digits in the machine. Each dial wheel 1 is provided with a pinion 5 on one side and with a cam 5 plate 4 having a cam 35 on the other, the pinion and the cam plate on either side of the dial wheel being connected by rivets or pins 43.

6 are gear wheels which are free to rotate on the stay 37, each wheel meshing with one of the pinions 5 while on the other side of the stay 37 its teeth are adapted to be engaged by the fingers 24, 25 of the corresponding disc 22a in the cylinder 22. 7 are tens-transfer levers which are also adapted to rock about the stay 8, one lever being provided for each cam plate 4 and equipped with a projection 11 which is adapted to be engaged by the projection 35 of the corresponding cam plate, as will appear from Fig. 1. The lever 7 is recessed at 38 so as not to be interfered with in its rocking movement by the stay 37 and the bosses of the wheels 6. 13 is a V-shaped surface at the end 12 of the lever 7.

16 are double-armed pawls which are free to rock on the stay 17, one pawl being arranged for each tens-transfer lever 7, equipped with two notches 14, 15 for the reception of the end 13 of the lever 7 at one end and a projection 18 at the other end, and connected with a pull-back spring 20 at the other end. Each spring 20 is threaded in a hole 19 at the end of its pawl 16, and all springs are anchored on the stay 21 with their free ends.

9 are overthrow detents which are arranged to rock on the stay 8 under the action of springs 10 which engage holes 9a in the detents 9, and are anchored at the stay 10'. A detent 9 is arranged for each gear and pinion unit 5, 6 and provided with projections 9b and 9c for alternately engaging between the teeth of the gear wheel 6. Normally, the detents are held with their projections 9b engaging the teeth of the corresponding gear 6 but when the gear is rotated by means which will be described, the projection 9b is moved out of the teeth of the gear wheel 6 and at the same time the projection 9c is caused to engage its teeth. This will occur after the gear wheel 6 has rotated through one half of its pitch and in this manner overthrowing of the dial 55 wheels 1 is prevented when the machine is operated at high speed.

Each tens-transfer lever 7 is provided with a cam 47 having two inclined cam faces 26, 27 at the side which is facing the roller 22, the cam faces forming a roof-shaped part as viewed from the left in Fig. 1, and 47a is a narrow projection on the cam which engages in the recesses of disks 22a as shown in Fig. 2.

65 The pawls 24 and 25 are arranged in ra-

dial recesses of the corresponding discs 22a and are fitted to rock about pins 29 which extend at right angles to the respective pawls 24 and 25. Each disc has a pair of pawls 24 and 25 and the pawls are pitched at an angle not quite 180 degs. in the successive discs, so that the last pawl is at an angle of about 140 degs. to the first pawl. The pawls are free to rock within their recesses, as shown for the pawl 25 in Fig. 2, and are held against one wall of their respective recess by means of a spring controlled piston 30 which is seated in a bore of the disc 22a. This is the normal or inactive position of the pawls in which they do not engage the teeth of the gear wheels 6 so that the rotation of the roller 22 is not transmitted to the corresponding gear wheel 6. The pawls 24, 25 are staggered in the several discs 22a. Viewed from the front of the machine, that is, from the right in Fig. 1, the row of pawls 24 for addition rises from the right end to the left end of the roller 22 and the row of pawls 25 for subtraction rises from the left end to the right end of the roller 22, so that the two sets of pawls make up two helical lines of opposite hands, which intersect at the centre of the roller.

On the side which is opposite the fingers 24, 25, each disc 22a is provided with two cams 23, 23 which are adapted to cooperate with the projection 18 at the end of the corresponding pawl 16. The arm of the pawl 16 at whose end the projection 18 is formed, is preferably curved substantially to the arc of a circle about the axis of the rotary cylinder 22. Preferably, the cams 23 are formed on separate cam plates 23' between the discs 22a.

Each gear wheel and pinion unit 5, 6 is combined with a change-over wheel 39 which may alternately assume the positions indicated in full and in dotted lines in Fig. 1. Racks 40 are provided for operating the totalizer and are moved to the left for winding up the totalizer mechanism, Fig. 1 showing the final position of a rack after the totalizer has been wound up. By rocking the totalizer frame on its fulcrum pins 41, 42, the gear wheel 6 or the pinions 5 are caused to mesh with the change-over wheels 39 according to whether such wheels are in the position shown in full lines or in dotted lines.

The operation of the totalizer is as follows:-

When the cam 35 on any of the dial wheel units 1, 4, 5 moves past the position corresponding to the digit "9", the tens-transfer lever 7 of this unit is moved into its active position by the cam 35 pushing the lever to the left in Fig. 1, throwing over the face 13 at the end 12 of the lever from the notch 14 into the notch 15 of the corresponding

pawl 16 and moving the cam 47 with its inclined faces 26, 27 within reach of the fingers 24, 25 and the pins 36, 36 on the corresponding disc 22a. The direction in which the dial wheel is rotated depends on the operation which is performed, being, for instance, clock-wise for addition, and anti-clock-wise for subtraction. For either direction, the direction in which the lever 7 is 5 rocked about the stay 8 by the cam 35 engaging its projection 11, is obviously the same. The cylinder 22 is now rotated through 180 degrees in a direction corresponding to the operation performed, addition or subtraction, one of the fingers 24, 25 is engaged by one of the inclined faces 26 or 27, according to the direction in which the cylinder 22 is rotated, and placed in operative relation with the teeth of the corresponding gear wheel 6 so that the gear wheel and consequently the pinion 5 of the corresponding dial wheel 1, rotates through one digit. Upon further rotation of the cylinder 22 in a given direction, one of the pins 36 strikes the cam 47 on the lever 7 and moves the end 13 of the lever from the notch 15 to the notch 14 in its pawl in which it is held by the spring 20. During the transfer, that is during the rotation of the cylinder 22, one of the cams 23 on the corresponding disk 22a of the cylinder 22 is opposite the projection 18 on the pawl 16 so that the pawl 16 is held against rotation about its stay 17 and the lever 7 is securely held in the notch 15.

When the cams 23 release the pawl 16 the pawl is free to rock about its stay 17 against the action of spring 20 as the end 13 of the corresponding tens-transfer lever 7 changes 40 from one of the notches 14, 15 to the other. The movement of the pawls 16 in this direction is limited by their projections 18 abutting against the perimeter of cylinder 22.

While the gear wheel 6 rotates, the over- 45 throw detent 9 is moved out of the teeth of the gear wheel, its projection 9b being raised, and the projection 9c engaging the teeth of the gear wheel after it has moved through one half of the pitch of the teeth. 50 In this manner, the projection 9c will enter an interstice between two teeth of the same gear wheel 6 and prevent overthrowing of the corresponding dial wheel 1 when the machine is operated at high speed.

55 I wish it to be understood that I do not desire to be limited to the exact details of construction shown and described for obvious modifications will occur to a person skilled in the art.

60 I claim:—

1. A calculating machine having a totalizer, dial wheels in said totalizer, a gear wheel operatively connected to each dial wheel, and a tens-transfer mechanism comprising a rotary cylinder, a pair of movable 65 fingers per gear wheel on said cylinder, a tens-transfer lever per pair of fingers which tens-transfer lever is adapted to place one of the fingers at a time in active position with respect to the teeth of the corresponding gear wheel, means controlled by the dial wheel corresponding to each pair of fingers for placing the corresponding tens-transfer 130

70 fingers per gear wheel on said cylinder, a tens-transfer lever per pair of fingers which tens-transfer lever is adapted to place one of the fingers at a time in active position with respect to the teeth of the corresponding gear wheel, means controlled by the dial wheel corresponding to each pair of fingers for placing the corresponding tens-transfer lever in active position with respect to the fingers of the corresponding pair, a pawl per tens-transfer lever with a pair of notches for engaging and holding said tens-transfer lever in two positions, means operatively connected to said pawl for moving its notched portion into engagement with said tens-transfer lever, a projection on the pawl, and a pair of cams per pawl on said cylinder adapted to cooperate with said projection so as to hold said pawl against movement during the tens-transferring operation, and pitched apart so as to receive said projection in their interstice for releasing said pawl.

2. A calculating machine having a totalizer, dial wheels in said totalizer, a gear wheel operatively connected to each dial 90 wheel, and a tens-transfer mechanism comprising a rotary cylinder, a pair of movable fingers per gear wheel on said cylinder, a tens-transfer lever per pair of fingers which tens-transfer lever is adapted to place one of the fingers at a time in active position with respect to the teeth of the corresponding gear wheel, means controlled by the dial wheel corresponding to each pair of fingers for placing the corresponding 95

100 tens-transfer lever in active position with respect to the fingers of the corresponding pair, a pawl per tens-transfer lever with a pair of notches for engaging and holding said tens-transfer lever in two positions, means operatively connected to said pawl for moving its notched portion into engagement with said tens-transfer lever, a projection on the pawl, and a pair of cams per pawl on said cylinder adapted to cooperate with said projection so as to hold said pawl against movement during the tens-transferring operation, and pitched apart so as to receive said projection in their interstice for releasing said pawl, the projection of said pawl being 105 adapted to bear on said cylinder in said interstice.

3. A calculating machine having a totalizer, dial wheels in said totalizer, a gear wheel operatively connected to each dial 110 wheel, and a tens-transfer mechanism comprising a rotary cylinder, a pair of movable fingers per gear wheel on said cylinder, a tens-transfer lever per pair of fingers which tens-transfer lever is adapted to place one of the fingers at a time in active position with respect to the teeth of the corresponding gear wheel, means controlled by the dial wheel corresponding to each pair of fingers for placing the corresponding tens-transfer 115

lever in active position with respect to the fingers of the corresponding pair, a double-armed rocking pawl per tens-transfer lever with a pair of notches at one end for engaging and holding said tens-transfer lever in two positions, a projection on the other end of the pawl, said other end being curved substantially to an arc of a circle about the axis of said rotary cylinder, and a pair of cams per pawl on said cylinder adapted to cooperate with said projection so as to hold said pawl against movement during the tens-transferring operation, and pitched apart so as to receive said projection in their interstice for releasing said pawl.

4. A calculating machine having a totalizer, dial wheels in said totalizer, a gear wheel operatively connected to each dial wheel, and a tens-transfer mechanism comprising a rotary cylinder, a pair of movable fingers per gear wheel on said cylinder, a tens-transfer lever per pair of fingers which tens-transfer lever is equipped with cam faces adapted to cooperate with said fingers for placing one of the fingers at a time in active position with respect to the teeth of the corresponding gear wheel, means controlled by the dial wheel corresponding to each pair of fingers for placing the corresponding tens-transfer lever in active position with respect to the fingers of the corresponding pair, a pawl per tens-transfer lever with a pair of notches for engaging and holding said tens-transfer lever in two positions, means operatively connected to said pawl for moving its notched portion into engagement with said tens-transfer lever, a projection on the pawl, and a pair of cams per pawl on said cylinder adapted to cooperate with said projection so as to hold said pawl against movement during the tens-transferring operation, and pitched apart so as to receive said projection in their interstice for releasing said pawl.

5. A calculating machine having a totalizer, dial wheels in said totalizer, a gear wheel operatively connected to each dial wheel, and a tens-transfer mechanism comprising a rotary cylinder built up from a plurality of disks, a pair of movable fingers on each disk, a spring in a recess of each disk for engaging a finger of the adjacent disk, a tens-transfer lever per pair of fingers which tens-transfer lever is adapted to place one of the fingers at a time in active position with respect to the teeth of the corresponding gear wheel, means controlled by the dial wheel corresponding to each pair of fingers for placing the corresponding tens-transfer lever in active position with respect to the fingers of the corresponding pair, a pawl per tens-transfer lever with a pair of notches for engaging and holding said tens-transfer lever in two positions, means operatively connected to said pawl

for moving its notched portion into engagement with said tens-transfer lever, a projection on the pawl, and a pair of cams per pawl on said cylinder adapted to cooperate with said projection so as to hold said pawl against movement during the tens-transferring operation, and pitched apart so as to receive said projection in their interstice for releasing said pawl.

In testimony whereof I affix my signature. 75
